Oscar A. Michel

ATTORNEY

UNITED STATES PATENT OFFICE.

MATHEW GESTRICH, OF ST. LOUIS, MISSOURI.

COLLAR-BUTTON.

1,373,234.

Specification of Letters Patent. Patented Mar. 29, 1921.

Application filed May 20, 1920. Serial No. 382,948.

To all whom it may concern:

Be it known that I, MATHEW GESTRICH, a subject of Austria-Hungary, residing at the city of St. Louis and State of Missouri, have 5 invented new and useful Improvements in Collar-Buttons, of which the following is a specification, reference being had to the accompanying drawings.

My invention relates to improvements in 10 collar buttons, and is especially directed to the type of buttons (as commonly employed to unite the ends of the neck band of an apparel shirt and to secure the back of a collar to the neck band) having hinged heads for 15 the facilitation of their insertion through the button holes of the collar and neck band.

My object is to provide a hinged head collar button of simple and inexpensive construction, whose various parts are capable of 20 production at a minimum of expense and which are held assembled by a single crimping of one of the parts.

My improvements consist in the novel construction, arrangement and combination of 25 parts as hereinafter fully, clearly and concisely set forth, definitely pointed out in my claims and illustrated by the accompanying drawing, in which:—

Figure 1 is a rear face view of a button 30 embodying my improvements.

Fig. 2 is a side or edge view of the button.

Fig. 3 is an enlarged vertical sectional elevation as taken on the line indicated $x-x$ of Fig. 1.

Fig. 4 shows the various elements in edge or side elevations relatively segregated.

Fig. 5 is a face view of the spring disk.

Fig. 6 is a face view of the bearing disk.

Fig. 7 is a face view of the hinged head, 40 and

Fig. 8 is an inverted sectional plan view taken on the line $y-y$ of Fig. 7.

Referring to the drawing, by numerals, 9 45 designates the "back" of the button which is constructed of sheet material and preferably formed into concavo-convex shape and provided with a continuous marginal flange 10.

The numeral 11 designates a spring-disk 50 constructed of resilient material such as sheet steel which as best shown in Fig. 3 is of lesser diameter than the back 9 whereby it may reside therewithin, and struck from the body of the disk 11 there is a pair of

spurs 12, arranged to project axially therefrom and which function to hold the button properly positioned by their engagement with the neck band.

The numeral 13 designates the bearing-disk, whose diameter is such as to permit it 60 to be fitted closely within the flange 10 of the back piece 9 and which is provided with the cut out 14 the pressed bearings 15 and the pair of perforations 16.

The hinged head comprises a substantially 65 disk-shaped body 17, a shank 18, bent at an angle relative to the body, a foot flange 19 and a pair of pintles 20.

All of the parts just recited are preferably, by reason of economy, made of sheet 70 material and by cutting and forming dies.

The assemblage consists in the placement of the spring disk 11 within the back 9, with the spurs extended outwardly away from the back, the hinged head is then related to 75 the bearing disk 13 by inserting its shank 18 through the cut out 14 and resting its pintles 20 in the pressed bearings 15 with the foot flange 19 projecting opposite the disk shaped body 17.

The bearing disk, with the hinged head is then placed within the flange 10 of the back with the foot flange 19 bearing against the spring-disk 11 and its pair of perforations 16 placed over the spurs 12 and then permanently secured by a crimping of the flange 10, as shown in Fig. 3.

It will be observed that the spring-disk is normally plane when the head is in functioning position and that the spring-disk is 90 bearing against the foot flange to hold the hinged head against movement. By manually exerting pressure on the head to swing it to open position, the foot flange as swung from the centers of the pintles depresses the 95 spring-disk and causes it to be bodily moved from the bearing-disk thereby allowing the foot flange to revolve about its pintles from closed or functioning position to open position, and which spring-disk tends to prevent 105 movement of the hinged head from either of its limits of movement.

What I claim:—

1. In a collar button of the class described, a head having an angular shank, 105 and a foot-flange, a pivoted support for the head, a spring-disk bearing against the foot-flange of the head, and a single element ar-

ranged to form a button back and a uniting means for the head, pivotal support and spring-disk.

2. In a collar button, a bearing-disk, a head having an angular shank for extension through the bearing-disk pintles for journaling in the bearing-disk, and a foot-flange, a spring-disk arranged to bear upon the foot-flange of the head, and a back having a 10 marginal flange serving as a means to hold all the parts assembled.

3. In a collar button of the class described, a head having an angular shank, and a foot flange, a pivotal support for the head, 15 a spring-disk bearing against the shank of the head, a single element of concavo-convex section arranged to form a button back and

a uniting means for the head, pivotal support and spring-disk, and a spur extending from the spring disk, for the purpose stated. 20

4. In a collar button, substantially a bearing disk, a head having an angular shank for extension through the bearing-disk pintles for journaling in the bearing-disk, and a foot flange, a spring-disk arranged to bear 25 upon the foot flange of the head, a normally plane back having a marginal flange serving as a means to hold all the parts in concavo-convex assemblage, and a spur extending from the spring disk, for the purpose 30 stated.

In testimony whereof I hereunto affix my signature.

MATHEW GESTRICH.
